(57) **CLAIM**

The ornamental design for a pickle pipe, as shown and described.

DESCRIPTION

FIG. 1 is a perspective view of a pickle pipe in a condition of use, showing our new design;

FIG. 2 is a top perspective view thereof;

FIG. 3 is a bottom perspective view thereof;

FIG. 4 is a side view thereof;

FIG. 5 is another side view thereof;

FIG. 6 is a top plan view thereof; and,

FIG. 7 is a bottom plan view thereof.

The dashed broken line showing of a mason jar and band in FIG. 1 depicts environmental subject matter that forms no part of the claimed design. The remaining dashed broken lines in the figures depict portions of the pickle pipe that form no part of the claimed design.

1 Claim, 5 Drawing Sheets
